(57) **CLAIM**

The ornamental design for a bench, as shown and described.

DESCRIPTION

FIG. 1 is a perspective view of a first embodiment of a bench of my new design, wherein the legs are shown in dashed lines;

FIG. 2 is a front elevation view of the bench shown FIG. 1; FIG. 3 is a rear elevation view of the bench shown in FIG. 1;

FIG. 4 is a left side elevation view of the bench shown in FIG. 1,

FIG. 5 is a right side elevation view of the bench shown in FIG. 1;

FIG. 6 is a top plan view of the bench shown in FIG. 1, FIG. 7 is a bottom plan view of the bench shown in FIG. 1; FIG. 8 is a perspective view of a second embodiment of a bench of my new design, wherein the legs are shown in solid lines;

FIG. 9 is a front elevation view of the bench shown FIG. 8; FIG. 10 is a rear elevation view of the bench shown in FIG. 8;

FIG. 11 is a left side elevation view of the bench shown in FIG. 8;

FIG. 12 is a right side elevation view of the bench shown in FIG. 8;

FIG. 13 is a top plan view of the bench shown in FIG. 8; and, FIG. 14 is a bottom plan view of the bench shown in FIG. 8.

The broken lines shown in the drawings illustrate portions of the article that form no part of the claimed design.

1 Claim, 12 Drawing Sheets
